WASHING MACHINE AGITATOR

Thomas R. Smith, Newton, Iowa, assignor to The Maytag Company, Newton, Iowa, a corporation of Delaware

Filed Sept. 26, 1966, Ser. No. 4,022

Term of patent 14 years

(Cl. D49—1)

Fig. 1

Fig. 2

FIGURE 1 is a perspective view of a washing machine agitator showing my new design; and,

FIGURE 2 is a top plan view of the agitator shown in FIGURE 1.

The sides not shown have substantially the same appearance as the side shown.

The dominant features of my design reside in the portions shown in full lines.

I claim:

The ornamental design for a washing machine agitator, as shown and described.
